ABACUS

Sylvester F. Don Dero, Baldwin, N. Y., assignor
to Daintee Toys, Inc., Brooklyn, N. Y., a cor-
poration of New York

Application March 28, 1952, Serial No. 279,145

4 Claims. (Cl. 35—33)

1

This invention relates broadly to educational apparatus and more particularly to an improved construction of hundreds frame or abacus.

One of the objects of my invention is to provide an improved construction of hundreds frame or abacus including means for enabling either the instructor or the student to readily remove or add beads to the rods which slidably support the beads.

Another object of my invention is to provide an improved construction of hundreds frame or abacus in which a multiplicity of rod members, supporting slidable beads, are displaceably mounted in the frame enabling quick removal and replacement of slidable beads with respect to the rod members by an arrangement of spring means coacting with circular inserts or guides mounted in one side of the frame.

Still another object of my invention is to provide a construction of hundreds frame or abacus which may be readily packaged for shipment, in disassembled arrangement, including supporting means for readily assembling and erecting the device when unpackaged.

Still another object of my invention is to provide an educational appliance of the abacus type which may be readily manufactured inexpensively on a mass production scale and effectively utilized by both instructors and students, by adding to, taking from, or interchanging beads on different rods of the device for use in connection with new methods of mathematical teaching.

Other and further objects of my invention reside in the construction of hundreds frame or abacus as set forth more fully in the specification hereinafter following by reference to the accompanying drawings, in which:

Figure 1 is a front elevational view of my invention with parts of the frame broken away and illustrated in section for more clearly showing the construction of the frame and the components constituting the mounting means and the displaceable arrangement of the rods which support the beads;

Fig. 2 is an end elevational view;

Fig. 3 is a vertical sectional view taken substantially on line 3—3 of Fig. 1;

Fig. 4 is a fragmentary vertical sectional view taken on line 4—4 of Fig. 1;

Fig. 5 is a horizontal sectional view taken substantially on line 5—5 of Fig. 1, and illustrating one of the displaceable rods in position for supporting the slidable beads, certain of the beads being shown in elevation;

Fig. 6 is a view similar to the view illustrated

2

in Fig. 5 but showing one of the rods displaced in position for removing or adding slidable beads thereon;

Fig. 7 is a horizontal sectional view on an enlarged scale through the frame of the abacus and illustrating one of the displaceable rods foreshortened and mounted for endwise movement through a circular insert or guide operating against a compression coil spring;

Fig. 8 is a side elevational view of one of the circular inserts or guides and illustrating particularly the annular chamfered edge thereof for facilitating the mounting of the insert or guide in the frame of the abacus after installation of the compression coil spring in an aligned socket in the frame;

Fig. 9 is a vertical sectional view through the insert or guide shown in Fig. 8, the view being taken on line 9—9 of Fig. 10;

Fig. 10 is a front elevational view of the insert or guide shown in Figs. 8 and 9;

Fig. 11 is a side elevational view showing the construction of compression coil spring used in the arrangement of my invention;

Fig. 12 is an enlarged cross sectional assembly view of the supporting means and the abacus frame in assembled position;

Fig. 13 is a view of the abacus frame in disassembled position prepared for shipment and illustrating particularly the manner in which the supporting means may be mounted within the abacus frame for facilitating packaging and shipment; and

Fig. 14 is a vertical sectional view taken on line 14—14 of Fig. 13.

In new methods of mathematical teaching being adopted by schools it is desirable when using a hundreds frame or abacus to provide means enabling either the instructor or the student to add to or take away from the individual rods of the abacus frame any number of slidable beads. It is also essential that such equipment be inexpensive in manufacture and production for meeting the available budget of educational institutions.

Wide distribution of the hundreds frame or abacus must be possible at low cost. I accomplish all of these requirements in the structure of my invention by providing erecting and mounting means which are readily removable from the hundreds frame or abacus and which may be installed within the frame and offer no projecting obstruction for facilitating packaging and shipment inexpensively. I provide mounting means for the multiplicity of spaced rods in the device

consisting of circular guides or inserts which are readily mounted in one of the interior sides of the frame for retaining compression coil springs in position within spaced sockets in the frame for individually acting upon the ends of the rods for cushioning the rods while enabling axial or longitudinal displacement thereof for a distance sufficient to free the rods individually from the frame while the ends thereof are guided by the circular inserts or guides to allow the slidable beads to be either removed from or added to the rods and the rods quickly replaced in latched position within the frame. The compression coil springs are shaped to provide end convolutions of reduced transverse section sufficient to provide a resilient abutment for the end of the displaceable rod which projects through the circular guide or insert. I have found the construction illustrated herein highly practicable and effective, but I desire it to be understood that no limitations upon my invention are intended and that the structure herein should be considered in the illustrative sense rather than in a limiting sense.

Referring to the drawings in more detail, reference character 1 designates the frame of the abacus formed by a pair of vertically extending end members 1a and 1b, interconnected by a pair of horizontally extending members 1c and 1d. The horizontally extending member 1d forming the bottom of the frame is provided with transversely extending recesses 2 and 3 therein, aligned with countersunk recesses through which screw threaded bolt members 4 and 5 extend. The heads of the bolt members 4 and 5 are retained in the countersunk recesses in the bottom frame 1d and are engaged by removable wing nuts 4a and 5a which fit within recesses as represented at 6a in Figs. 1 and 12 and 6a and 7a in Fig. 13, for example, within the foot supports represented at 6 and 7. The foot supports 6 and 7 have widths corresponding to the widths of the transverse slots 2 and 3 and a thickness corresponding to the thickness of the frame members 1a and 1d. The width of the foot supports 6 and 7 is such that the foot supports clear the slidable beads 10a on the rods 9a and 9j, respectively, when the foot supports 6 and 7 are positioned in coplanar alignment with the rails 1c and 1d. The foot supports 6 and 7 are initially packaged with the frame 1 as shown in Fig. 13 by means of a suitable binding tape 6b and 7b by which the foot supports may be conveniently packaged in coplanar alignment with rails 1c and 1d and shipped with the frame without offering projecting obstruction and also being ready for immediate assembly of the device.

In Figs. 1-3, 5, 6, 12 and 13, the foot supports 6 and 7 are shown in assembled position with the wing nuts 4a and 5a clamping the foot supports 6 and 7 within transverse recesses 2 and 3 and with the headed ends of the bolt members 4 and 5 countersunk within the horizontally extending member 1d.

The vertically extending member 1a is provided with a multiplicity of horizontally extending spaced recesses shown at 8a, 8b, 8c, 8d, 8e, 8f, 8g, 8h, 8i, and 8j for slidably receiving and retaining the ends of the spaced horizontally extending rods 9a, 9b, 9c, 9d, 9e, 9f, 9g, 9h, 9i and 9j. The horizontally extending rods 9a-9j each slidably receive the groups of beads which I have represented at 10a, 10b, 10c, 10d, 10e, 10f, 10g, 10h, 10i and 10j. The opposite ends of the rods 9a-9j fit within the circular inserts or guides il-

lustrated more particularly in Fig. 4 at 11a, 11b, 11c, 11d, 11e, 11f, 11g, 11h, 11i and 11j. These circular inserts or guides are shaped as shown more particularly in Figs. 8-10 to provide a chamfered annular peripheral edge as represented at 11a', facilitating the insertion of the circular insert or guide into the side wall of the end member 1b as shown for example by recess 12a in Fig. 7. The guide 11a is provided with a surface coating or glue on the cylindrical surface thereof represented at 14. This glue adheres to the interior surface of recess 12a and retains the circular insert or guide shown at 11a in position in end member 1b. The recesses represented at 12a are each aligned with horizontally extending sockets represented at 15 in Figs. 5, 6 and 12. The sockets represented at 15 are in line with the recesses represented at 8a-8j in the vertically extending end member 1a. Before insertion of the guides 11a-11j in position, a compression coil spring, represented at 16, is inserted in each of the sockets represented at 12a. The depths of sockets 8a-8j in frame member 1a are proportional to the depths of the aligned sockets 15 in frame member 1b, such that rod members 9a-9j may be selectively displaced to the right against the pressure offered by the biasing springs 16 and through the inserts or guides 11a-11j for a sufficient distance to allow the ends of the rods 9a-9j to clear the sockets 8a-8j and to be removed from the frame as represented in Fig. 6, or tilted at a sufficient angle to enable the slidable beads 10a to be removed from or inserted over the ends of the rods. Thereafter the rods are selectively reinstalled by linearly moving the rods against the pressure of the compression coil springs 16 through guides 11a-11j and the first mentioned end portion of the rods again reintroduced into sockets 8a-8j with the coil springs 15 continuously biasing the rods to latched positions.

Each compression coil spring 16 is shaped to provide end portions of reduced section at 17 and 18 of a sufficiently reduced diameter as to abut with and bear upon the end of the aligned displaceable rods as shown for example in Fig. 7. That is to say, reduced section 17 of the coil spring 16 has a diameter that is slightly less than the internal diameter of the insert or guide 11a so as to eject the rod 9a through the insert or guide so that its remote end abuts with the end wall of the socket shown at 8a in end frame member 1a. The guide 11a extends over the end of the socket 15 sufficiently to confine the larger convolutions of the coil spring 16 and prevent the loss of the spring out of the frame member 1b. The compression coil spring 16 is symmetrically shaped at each end in order to simplify the assembly process.

In the operation of the abacus the rods are assembled as shown in Fig. 5 with the compression springs urging the rods linearly toward the left. When it is desired to remove or add to the number of beads, the rod is moved linearly toward the right against the pressure of the spring and guided by the circular member or guide 11a freeing the end of the rod 9a from socket 8a and enabling the beads 10a to be removed from or added to the rods. The several rods are manipulated in a similar manner enabling the number of beads to be increased or decreased on the different rods.

The hundreds frame or abacus of my invention, together with the beads, are preferably manufactured from wood including the inserts

or guides **11a-11j**, but the device including the inserts or guides may be made from molded plastic.

While I have described my invention in one of its preferred embodiments I realize that modifications may be made and I desire that it be understood that no limitations upon my invention are intended other than those that may be imposed by the scope of the appended claims.

What I claim as new and desire to secure by Letters Patent of the United States, is as follows:

1. An abacus comprising a frame provided with a socket in one end thereof, a rod having a multiplicity of co-acting slideable beads thereon, said rod having an end portion slidably insertable into said aforementioned socket, the other end of said frame having a recess therein, an annular guide apertured centrally thereof and inserted in said recess, a socket disposed behind said recess and in the last mentioned end of said frame, and a compression coil spring mounted in said socket and having the radius of the end turns thereof reduced in section and aligned with and bearing upon the end of said rod inserted through said guide for yieldingly biasing said rod linearly into engagement with the socket in said first mentioned end of said frame.

2. An abacus as set forth in claim 1 in which said annular guide is provided with a chamfered peripheral edge facilitating the entry thereof into the recessed frame and in which said annular guide is maintained in the recess by a layer of cement for fastening the annular guide to the frame.

3. An abacus as set forth in claim 1 in which

5 5 said compression coil spring has similarly disposed end turns formed on radii which are reduced for providing end turns of diameters substantially conforming with the diameter of the end of the rod which extends displaceably through the annular guide.

10 10 4. An abacus as set forth in claim 1 in which said annular guide has an external diameter exceeding the diameter of the aligned socket in the recessed frame and an internal diameter less than the internal diameter of the said aligned socket and substantially equal to the external diameter of the displaceable rod and wherein said compression coil spring has opposite end turns 15 15 formed on radii which are reduced for providing end turns of diameters substantially conforming with the internal diameter of said annular guide and the external diameter of said displaceable rod.

20 20 SYLVESTER F. DON DERO.
